STARTING EQUIPMENT FOR DIESEL ENGINES

Fred G. Hudson and Leslie A. Smith,
Seattle, Wash.

Application December 26, 1933, Serial No. 703,956

2 Claims. (Cl. 123—30)

This invention relates to improvements in internal combustion engines and it has reference more particularly to engines of the relatively high compression types operating on the Diesel or semi-Diesel principle; the invention being based upon the provision of an auxiliary means for starting the engine to build up the necessary conditions for normal Diesel operation.

It is the principal object of this invention to provide a relatively inexpensive starting equipment adapted to be built into, or attached permanently to the engine, and designed to utilize a carbureted fuel; the equipment also having a novel valve system and an ignition means associated therewith whereby the engine, during the starting operation in particular, will be temporarily converted into one operating on the usual gas engine principle.

It is also an object of the invention to provide a starting equipment of the above stated character, having a manual control or "setting" lever so arranged in combination with control parts for the Diesel operation that its adjustment to starting position will automatically render certain parts of the Diesel equipment ineffective so as not to interfere with proper functioning of the starting equipment. Likewise, when the lever is adjusted back to "off" position, it automatically renders the starting means inoperative and resets the Diesel equipment.

It is also an object of the invention to provide, in the starting equipment, an expansion chamber supplementary to the combustion chamber already provided so that a necessary reduction of pressure for satisfactory firing of the compressed starting charges from the carburetor may be obtained.

More specifically stated, this invention resides in the provision of a starting equipment adapted to operate in conjunction with part of the Diesel equipment, comprising an auxiliary expansion and combustion chamber, which may be opened into direct communication with the cylinder explosion chamber through a valved passage, and having means for the admittance of carbureted fuel charges into the auxiliary chamber incident to suction created by downward travel of the engine piston, and including an ignition system for firing the admitted fuel charge after it has been suitably compressed by upward travel of the piston, thereby to give the engine its starting impulse; whereupon, the cycle of charge-admitting compressing, firing and exhausting continues to be repeated until the starting equipment is manually adjusted to "off" position.

thereby to cause normal functioning of the Diesel equipment.

Other objects of the invention reside in the various details of construction and in the combination of parts and in their mode of operation as will hereinafter be described.

For accomplishing these and other objects of the invention, we have provided the improved details of construction, the preferred forms of which are illustrated in the accompanying drawings, wherein—

Fig. 1 is a cross sectional view, on the axial line of a cylinder, of a Diesel engine equipped with a starting apparatus embodied by the present invention.

Fig. 1a is a sectional detail of the injection lever mounting eccentric.

Fig. 1b is a cross section view on line b—b on Fig. 1a.

Fig. 2 is a horizontal, cross section view taken on the line 2—2 on Fig. 1.

Fig. 3 is an enlarged, cross section view on the line 3—3 on Fig. 1, through the cylinder head.

Fig. 4 is a top, or plan view of the cylinder head and starting equipment; certain parts being shown in section for purpose of better illustration.

Fig. 5 and Fig. 6 are views diagrammatically illustrating the control devices and positions of the valves in the equipment for Diesel operation and for the starting operation, respectively.

Fig. 7 is a sectional detail on the line 7—7 on Fig. 4.

Referring more in detail to the drawings—

In Fig. 1, the reference numeral 1 designates, in its entirety, a common form of Diesel engine. This engine comprises a cylinder 2, with a piston 4 reciprocable therein and connected by rod 4 with a crank shaft 5. A cam shaft 6 is rotatably driven in timing with the crank shaft through suitable gearing, (not shown). In the cylinder head 8 are exhaust and air inlet passages 9 and 10 controlled, respectively, by tappet valves 11 and 12. These valves, as shown in Fig. 3, have their mounting stems slidably mounted in guides 13 and the said valves are yieldingly held closed by coiled springs 14 which surround them and seat against the guides and against nuts 15 on the upper ends of the stems.

Operation of the valves 11 and 12, in the normal working of the engine, is effected by the action of rocker arms 16 and 17 respectively. These arms, as shown in Figs. 5 and 6, are pivotally supported on a pivot shaft 18 and have their inner ends overlying the stems of valves 11 and 12 and their outer ends operatively con-

nected for actuation by push rods, as at 19 and 20, actuated by cams as at 21, on the cam shaft 6. It is to be understood that these are parts of the Diesel engine construction and are not, in 5 the relationship so far described, a part of the invention.

The present starting equipment comprises an auxiliary combustion and expansion chamber 25 in a housing 26 attached to the engine head. 10 This chamber 25 communicates directly with the air inlet passage 10 and, when valve 12 is open, it is opened into communication with the upper end of engine cylinder 2 (Fig. 4). At the outer end of chamber 25 there is a port 28 opening into 15 a passage 29 which connects at one side of the port with a carburetor 30 and at the other end is open to outside air. A valve 31 is mounted in the passage 29 between the port 28 and carburetor and there is a valve 32 at the other side of the 20 port. These valves have operating shafts 33—34, respectively, as shown in Fig. 4, and on the shafts are lever arms 35 and 36, respectively, connected by a link 37 so that they are moved in unison and their relationship is such that 25 when valve 31 is opened, the valve 32 will be closed. Likewise, when valve 31 is closed, the valve 32 will be opened.

There is also a tappet valve 38 for the port 28 and this valve is yieldingly held closed by a 30 coiled spring 40 that surrounds the valve stem 38' and bears against a retainer 41 on the outer end of the stem. This valve 38 may be held open by the movement against the outer end of the valve stem 38' of a lever 42 that is pivotally 35 supported at one end by a pivot 43 fixed in a bracket 44 attached to the cylinder head or other part on the engine. This lever has a link 45 connecting its swinging end with a horizontally disposed hand lever 47 attached by a pivot 48 40 to a bracket 48' upon the cylinder head. The swinging of the hand lever effects the functional movements of the lever 42 to hold open or permit the closing of valve 38.

As will be observed by reference to Fig. 4, the 45 hand lever 47 is supported pivotally at a point 48 between its ends. The link 45 is connected to the lever 47 at a point outside the pivot 48 and its inner end is adapted to be swung, as indicated in Fig. 4, into a position across and against the inner end of rocker lever 17 to swing it 50 downwardly against the stem of the valve 12 to hold the valve open, as seen in Fig. 3. At the inner end of the lever 47 there is a cam surface 47a, as shown in Fig. 7, which facilitates the riding of the lever arm on to the rocker lever 17, thereby to actuate the valve 12 to open position. This places the chamber 25 in communication 55 with the combustion cylinder and provides the increased volume whereby a necessary reduction in compression is effected for starting on the present equipment.

When the hand lever 47 is in the position for holding the valve 12 open, the lever 42, connected thereto by link 45, is adjusted outwardly to that 60 position, as shown in Fig. 6, in which the valve 38 is permitted to be closed by spring 40. When the lever 47 is swung to a position to free the valve 12 so that it may close, it swings the lever 42 inwardly against the outer end of the valve 65 stem 38' to hold the valve 38 open as shown in Fig. 5.

The two valves 31 and 32 are connected by link 70 37 to work together and are moved between their different positions by a connection with the link 75 45. This connection comprises a lever arm 50

fixed to the shaft of valve 31 and joined pivotally by a link 51 to the link 45. This linkage provides that when the lever 47 is adjusted to starting position, as shown in Fig. 6, the valve 31 will be opened and the valve 32 will be closed, thereby 5 causing suction to draw in fuel charges through the carburetor and past the inwardly yieldable valve 38. When the hand lever is adjusted to running position as shown in Fig. 5, it releases the valve 12 for normal action by the rocker 10 arm 17 and closes valve 31 and opens valve 32, thereby cutting out the carburetor connection and opening the inlet passage 10 to outside air past the valves 32 and 38. It is to be understood that the arrangement of linkage and design of 15 parts is such that valve 32 will be opened and valve 31 closed prior to the releasing of valve 12 for Diesel operation.

The engine also has the usual injection nozzle 60 through which oil charges are delivered to 20 the cylinder when under Diesel operation and this is under control of a mechanism comprising a lever 61 pivotally mounted at one end by a pivot 62 at the upper end of a post 63 fixed 25 on the engine head 8. The lever 61 extends 30 across the nozzle valve stem and is adapted to be lifted by a push rod 64 acted on by a cam 66 on shaft 6. The pivot 62 is in the form of an eccentric, as seen in Figs. 1a and 1b, and is revoluble in supports 66 and has a crank arm 35 67 at one end connected by a link 68 with lever 47, as shown diagrammatically in Fig. 6, so that when the latter is adjusted to a position for throwing the starting carburetor into operation, as shown in Fig. 6, it rotates the eccentric 35 to lift the lever 61 clear of the injection valve 60 and thus to prevent ejection of Diesel fuel while the engine is being operated on the starting carburetor.

Assuming the parts to be so constructed and 40 associated with the engine structure as illustrated, the operation of the invention is as follows:

To start the engine, the operator first swings the lever 47 to the full line position of Fig. 4 45 at which its inner end engages the rocker lever 17 to depress the lever to hold the valve 12 open. The lever 42 then disengages the stem of valve 38 and allows the valve to be held yieldably 50 in closed position by spring 40. This positioning of the lever 47 also causes the eccentric 62 to be rotated in a manner to lower the injection lever 61 to non-injecting position. Also, this adjustment of lever 47 causes valve 31 to be opened and valve 32 to be closed. The parts then assume 55 the position of Fig. 6. Then, by turning over the crank shaft, the piston will be reciprocated and on its downward stroke will create a partial vacuum in the upper end of cylinder 1 and in the chamber 25 and this, by suction, causes a fuel 60 charge to be drawn into the chamber 25 past valve 38. Upward travel of the piston compresses the admitted charge and it is ignited in proper timing by means of a spark plug 70 mounted in a wall of chamber 25 as seen in Fig. 1, and connected in a circuit controlled by the usual ignition system not herein shown.

The ignition of the charge causes an explosion 65 whereby the piston is forcibly driven down thus to carry the engine crank shaft over for another 70 cycle. After a succession of these explosions, the engine will be in condition for its normal Diesel operation whereupon the lever 47 is adjusted back to "off" position as shown in Fig. 5.

This equipment, unlike some prior devices used 75

for starting, retains the full fuel charge that is drawn in, this being possible by reason of the increased volume for compression.

The equipment illustrated is simple and relatively inexpensive and may be made either as regular built-in equipment or as an attachment. It does away with the auxiliary device usually provided for starting purposes and if necessary could be used for operating the engine.

Having thus described our invention, what we claim as new therein and desire to secure by Letters Patent is—

1. The combination with an engine of the Diesel type, having a working cylinder, a cylinder head equipped with a fuel injection system and with air inlet and exhaust passages for the cylinder, valves for controlling said passages and means for synchronously operating the valves in normal Diesel operation, of a starting attachment fixed to the head and comprising a housing formed with an auxiliary combustion chamber in open communication with the air inlet passage and having an intake opening, an ignition means in said chamber, a carburetor having a suction passage communicating with said combustion chamber through said intake opening and having an outside opening, a valve for closing said outside opening, an automatic valve in the said intake opening and a manually adjustable starting member operatively connected with said valves and injection system whereby in normal Diesel operation said automatic valve and said valve in the outside opening are held open, and movable to starting position, thereby to render the fuel injection system inoperative, and to move the valve in the said outside opening to closed posi-

tion and to free the automatic valve for automatic operation under influence of internal pressures.

2. The combination with an engine of the Diesel type having a working cylinder, a cylinder head equipped with a fuel injection system and with air inlet and exhaust passages for the cylinder, valves for controlling said passages, and means for synchronously operating the valves in normal Diesel operation, of a starting attachment fixed to the head and comprising a housing formed with an auxiliary combustion chamber in open communication with the air inlet passage and having an intake opening, an ignition means in said chamber, a carburetor having a suction passage connected at one end with the carburetor and open to outside air at its other end and communicating at a point between its ends with said intake opening, a normally open closure valve for the open end of the suction passage, a normally closed carburetor control valve in the passage between the carburetor and the intake opening, an inwardly yieldable valve in the intake opening and a starting lever having means operatively connecting it with the injection system and with said yieldable valve whereby in "off" position the yieldable valve is held open and the carburetor valve is closed and movable to "starting" position whereby the fuel injection system is rendered ineffective, the control valve of the air inlet passage in the cylinder head is held open, the inwardly yieldable valve is freed for automatic operation under influence of pressure differential, the carburetor control valve is opened, and the valve to outside air is closed.
